HOIST CONTROL MECHANISM

Henry H. Logan, Chicago, Ill., assignor to Logan
Engineering Co., Chicago, Ill., a corporation of
Illinois

Application May 17, 1946, Serial No. 670,640

11 Claims. (Cl. 192—144)

1

My present invention relates generally to hoist control mechanisms, and more particularly to mechanical devices adapted to use in conjunction with other electrical and mechanical hoist control apparatus for automatically controlling certain phases of the hoist operation.

One of the objects of this invention is to provide a hoist control mechanism adapted to be driven from the hoist drum for effecting automatic control of hoist movements and wherein the operating parts are so constructed and arranged that they function within an enclosure and are readily lubricated.

As another object my invention comprehends the provision of a hoist control mechanism which, although adapted to compact construction and the occupation of a relatively small space, effects accurate and consistent control of a hoist without requiring extreme accuracy in the machining of incorporated parts.

It is a further object of my present invention to provide a hoist control mechanism wherein cams are utilized to effect automatic control of the hoist operation after the hoist is manually started by an operator, and wherein said cams remain stationary during the major portion of the hoist travel and are rendered effective for control purposes near and at the ends of the hoist travel.

An additional object of the invention is to provide a hoist control mechanism of the type referred to in which the automatic control of the mechanism may be supplemented at any time by the manual control of the operator.

Other objects and advantages of the invention will be apparent from the following description and the accompanying drawings, in which similar characters of reference indicate similar parts throughout the several views.

Referring to the drawings, of which there are five sheets,

Figs. 1, 2 and 3 are, respectively, front, side and rear elevational views of a hoist control mechanism embodying a preferred form of my present invention;

Fig. 4 is a fragmentary side sectional view of a portion of the mechanism shown in Figs. 1, 2 and 3, wherein the section is taken substantially on a line 4—4 of Fig. 5 and in the direction indicated by the arrows;

Fig. 5 is a front elevational view of a portion of the mechanism shown in Fig. 4 with the cover removed so that the view is effectively taken substantially on a line 5—5 of Fig. 4 and in the direction indicated by the arrows; and

2

Fig. 6 is a fragmentary and partially diagrammatic view which illustrates schematically a portion of the hoist-operating and control parts with which my preferred control mechanism is adapted to operate.

The hoist control mechanism disclosed herein for illustrative purposes is adapted to operate in conjunction with a part of the hoist-operating mechanism, such as the hoist drum, which has a position correlated to that of the hoist. In its operation my disclosed control mechanism functions in conjunction with other parts of the hoist control apparatus, such as the electrical controls for an electrically operated hoist, to supplement the manual control of the hoist by affecting automatic control of the hoist deceleration and speed during its travel and automatically stopping the hoist at predetermined normal positions. In my preferred construction, however, the automatic control effected by the disclosed mechanism may be supplemented by manual control when such manual control is necessary or desirable because of an abnormal condition or circumstance.

As a practical matter, the acceleration and deceleration of the hoist normally occur at the extremities of its movement between the predetermined stopping positions. The speed of the hoist in the intermediate portion of the travel between those positions is virtually uniform. It, therefore, follows that if the controlling portion of the hoist control mechanism travels continuously during the movements of the hoist, it must be unduly large, especially in instances in which the hoist travel is long, in order to provide the required accuracy and rate of control near and at the ends of the movements. In the present exemplary embodiment of my invention, I have disclosed a hoist control mechanism in which the controlling portions of the mechanism are not only accurate and positive in their action, but the size of the mechanism is materially limited by virtue of the fact that those controlling portions function by movement only during the desired variable portions of the hoist travel.

In addition to the foregoing features, the construction and arrangement of my hoist control mechanism are such that its mechanical driving parts operate within an enclosure with an adequate supply of lubricant and so as to be protected from dirt.

Having reference to the accompanying drawings, and particularly to Figs. 1, 2 and 3, my hoist control mechanism has a base 10 which provides a main support for the operating parts and in-

cludes a flanged lower portion 12 by which the mechanism may be secured to a suitable foundation.

On one end of the base 10 and intermediate the top and bottom thereof, a flanged gear box 13 is removably secured thereto by fastening means, such as cap screws 14. Removably secured to the outer end of the gear box 13 by cap screws 15 is a flanged end cover 16. A shaft 17 extends through an opening in the end cover 16 and is journaled in bearings 18 and 19 supported in spaced relationship within the end cover 16 and gear box 13, respectively. Within the gear box 13 and adjacent a shoulder 20 on the shaft 17 a pinion 22 is drivingly connected to the shaft and disposed between the bearings 18 and 19. The shaft 17 projects outwardly from the end cover 16 and is desirably provided with a keyway 23 so that it may be connected to a portion of the hoist mechanism, which is continually dependent upon the hoist position, to be driven thereby.

At its top the base 10 has a main bearing bore 24, as shown in Fig. 4, the axis of which is parallel to the axis of the shaft 17. In the disclosed structure, sleeve bearings 25 and 26 are mounted in opposite ends of the main bearing bore 24 and rotatably support a hollow hub 27 which is coaxial with and projects from one end of a substantially cylindrical drum 28. Desirably, the hub 27 is integrally formed with the drum 28 and is connected thereto through an intermediate supporting web 29. A shoulder 30 on the supporting web 29 adjacent the inner end of the hub 27 engages a projecting flange 32 at the inner end of the main bore 24 axially to locate the drum and hub relative to the base. At the outer end the hub is secured in place by fastening means, such as a removable collar or nut 33, which abuts a shoulder 34 on the hub and extends radially to overlap the base at the end of the bore 24 opposite the projecting flange 32.

By preference, a circumferential channel 35 is provided in the interior of the main bearing bore 24 between the bearings 25 and 26 and radial passages 36 extend through the hub 27 to provide communication for the flow of lubricant from a circumferential channel 37 in the mid-portion of the interior of the hub 27 to the channel 35 and thence to the surfaces of the bearings 25 and 26.

Sleeve bearings 38 and 39 are mounted in the opposite ends of the hollow hub 27 rotatably to support a shaft 40 in coaxial relationship to the hub 27 and bearings 25 and 26. At each end the shaft 40 extends beyond the ends of the hub. A gear 42 is mounted on the outer end of the shaft 40 and is drivingly connected thereto by means, such as a key 43. The gear 42 meshes with the pinion 22 so that the shaft 40 is driven by force applied through the shaft 17. As illustrated in Fig. 2, an upper housing 44 adjoins the upper portion of the gear box 13 and the upper portion of the base adjacent the end of the main bearing and provides an enclosure for the gear 42.

The other end of the shaft 40 extends into the interior of the cylindrical drum 28 and has a pinion 45 drivingly secured thereto by means, such as a key 46, as shown in Fig. 4. A spacing washer 47 is desirably provided at the end of the shaft 40 between the pinion 45 and the inner end of the hub.

At a position displaced from the axis of the shaft 40, the supporting web 29 of the drum carries a stud shaft 48 which extends axially of the drum and has portions 49 and 50 of different diameters connected by a tapered mid-portion 52.

For supporting and securing the stud in position relative to the supporting web 29, in the present instance, I have provided an integral and axial extension 53 on the end of the stud adjacent the portion 49 which extends through a bore 54 in the supporting web and has its end threaded to receive a nut 55 which holds the stud in place. By preference, a spacing washer 56 is mounted on the axial extension 53 of the stud and is secured between the inner face of the supporting web 29 and a shoulder 57 on the stud. The washer 56 extends outwardly beyond the periphery of the portion 49 of the stud.

A cluster gear 58 has an axial bore 59 of diameters such that it fits over the portions 49, 50 and 52 of the stud and has sleeve bearings 60 and 62 secured in opposite ends thereof for rotatably supporting the gear on the portions 49 and 50 of the stud. At its inner end the cluster gear 58 is spaced from the supporting web 29 of the drum by the face of the washer 56 which extends radially beyond the periphery of the stud portion 49. The cluster gear 58 includes as integral parts a gear 63 and a pinion 64. The gear 63 is substantially flush with the inner end of the cluster gear and meshes with the pinion 45 on the inner end of the shaft 40 to be driven thereby. At the outer end of the stud 48 and adjacent the end of the pinion 64, additional support is provided for the outer end of the stud by a bearing block 65 which has a bearing bore 66 through which the end of the shaft extends and which is secured by fastening means, such as screws 61, to suitable bosses on the interior of the drum (Figs. 4 and 5).

As depicted in Figs. 4 and 5, a bracket 68 is integrally formed on the interior of the drum and has side walls 69 extending in an axial direction into the drum from the supporting web 29. In the disclosed structure, the position of the bracket 68 is eccentric to the axis of the drum and displaced toward the side of the drum opposite that upon which the stud 48 is secured. The side walls 69 of the bracket are spaced from opposite sides of the shaft 40 and pinion 45. A plate 70, having a stud shaft 72 integral therewith, is secured to the projecting ends of the walls 69 by fastening means, such as cap screws 73. The axis of the outwardly projecting stud shaft 72 is parallel to the axis of the drum and eccentrically disposed relative thereto.

A driven gear 74 has a sleeve bearing 75 rotatably carried on the stud shaft 72 and is axially spaced from the surface of the plate 70 by a spacing washer 76. At its outer end, the gear 74 is held in place on the stud 72 by a cap 77 which is removably secured to the end of the stud by fastening means, such as a screw 78, and has a marginal portion overlapping the end of the gear hub. Rotation of the cap 77 relative to the end of the stud is desirably prevented by means, such as a pin 79, extending through the cap and axially into the end of the stud shaft at one side of the screw 78. When thus mounted, the gear 74 meshes with the pinion 64 of the cluster gear to be driven thereby.

The outer marginal portion of the driven gear 74 adjacent the teeth thereof is provided with a faced front surface 80 which faces outwardly toward the end of the drum. In the mid-portion 70 of the faced surface 80, a circumferential T slot 82 is provided to retain a plurality of outwardly projecting fastening elements, such as cap screws 83. At at least one position around the gear, an opening 84 extends from the T slot 82 to the rear surface of the gear through which

the fastening elements are inserted into the slot. The fastening elements, thus held in the T slot and movable circumferentially of the gear, are utilized for adjustably securing stops 85 and 86 against the faced surface 80 of the gear.

Axially of the drum, the stops 85 and 86 are aligned with the side surfaces 65x and 65y of the bearing block 65. The stops 85 and 86 have outwardly projecting portions 81 and 88, respectively, which are adapted to engage the opposite side surfaces 65x and 65y of the bearing block 65 when the driven gear is rotated to either of the positions for effecting such engagement. One of the stops engages one side of the bearing block upon rotation of the gear in one direction and the other of the stops engages the other side of the bearing block upon rotation of the gear in the opposite direction. When such engagement of either of the stops with one side of the bearing block 65 occurs during the rotation of the driven gear, that driven gear is no longer free to rotate relative to the drum 28 and the stop serves as a driving connection to the drum and through which the drum is driven by the continued application of driving force through the shafts 17 and 40 and the various gears. Thus the drum-driving mechanism, which comprises the various shafts and gears, provides for an intermediate period of rotation of the gears when they are actuated by the hoist-driving mechanism, which intermediate period of rotation is terminated at either end by a period in which the drum is driven in response to the hoist movement.

In order to provide a sealed closure within the drum 28 to protect the parts enclosed therein from dirt and to hold a supply of lubricant for the gears and bearings, an end plate 89 is secured to the outer end surface of the drum by fastening means, such as a series of screws 90. A knob 92 at the mid-portion of the outer surface of the end plate 89 provides a handle for the removal and placement of the end plate.

Although there are various ways in which the drum 28 might be biased to a normal position of rest, I prefer to accomplish this result by the use of suspended weights, such as 93, which are connected to the drum through a flexible cable 94 and a coupling yoke 95, as shown in Figs. 1, 2 and 3. The yoke 95 is rotatably connected to a lug 96 by a pin 87, which lug is secured to the periphery of the drum at the end of the drum which is adjacent the base 10. At the top of the base 10 a bracket 98 is secured thereto by suitable fastening means, such as cap screws 99, and has at its top pulley-carrying arms 100 and 102 extending toward opposite sides of the base and optionally usable, depending upon the side of the base at which the weights 93 may be more conveniently suspended. In the present instance, and as shown in Figs. 1, 2 and 3, guide pulleys 103, 104 and 105 are rotatably mounted upon the bracket arm 102 by suitable supporting pins 106, 107 and 108, respectively. The pulleys 103, 104 and 105 are mounted in positions and are so angularly disposed that they guide the cable 94 upwardly from the lug 96 and to a position of suspension at one side of the base such that the weights 93 are free to move vertically with the cable.

When the drum 28 is free to turn, as in an instance when it has been driven to an extreme position in one direction and then the driving force is reversed, the biasing force of the weights moves the drum to a position such that

the lug 96 is adjacent one side of the pulley 103. The biasing force of the weights 93 also holds the drum in its normal position when neither of the stops 85 or 86 is in engagement with the side surfaces 65x and 65y of bearing block 65. However, a groove 109 is provided in the periphery of the drum in alignment with the lug 96 so that when the drum is rotated by force applied through the drum-driving shafts and gears, the cable 94 will be wound around a portion of the periphery of the drum and retained in the groove. With the particular biasing system disclosed, the movements of the drum are preferably limited to less than one-half of a revolution from the normal position in either direction.

On its outer surface, the drum 28 has a plurality of axially separated and radially projecting cam-carrying flanges 110, 112 and 113. One of the radial faces of each cam-carrying flange 110, 112 and 113 has therein a circumferential T slot adapted slidably to receive a plurality of axially projecting fastening elements, such as bolts 114 (Fig. 1); said T slots in the respective flanges being designated by the numerals 115, 116 and 117. In at least one circumferential position on each of the flanges, a bore 118 (Fig. 4) opens into the wider portion of each of the T slots to provide an opening for the insertion of the fastening elements into the slots.

As shown in Figs. 1 and 2, cams 119 and 120 are adjustably secured in circumferentially and axially displaced positions upon the cam-carrying flanges 110 and 112, respectively, by the fastening elements 114 and coacting nuts 122. In like manner, in the instance of the presently disclosed structure, a plurality of cams 123 and 124 are adjustably secured in circumferentially displaced positions to the cam-carrying flange 113.

In the disclosed embodiment of my invention, cam followers comprise rocker arms 125 and 126 mounted for swinging movement on a shaft 127 which is secured to and projects from the base 10 in a direction parallel to the axis of the drum and in a position displaced to one side of the drum. The rocker arms 125 and 126 have intermediate bearing portions 128 and 129, respectively, mounted on the shaft. One end of the bearing portion 128 abuts a boss 130 on one side of the base and the two bearing portions are separated by a spacer collar 132. At the outer end of the shaft a collar 133 holds the bearing portions in their positions upon the shaft. On opposite sides of the bearing portion 128 of the rocker arm 125, oppositely projecting arms 134 and 135 carry cam-following rollers 136 and 137, respectively, which are aligned for coaction with the cams 119 and 120. The rocker arm 126 desirably has only one laterally projecting arm 138 and carries a roller 139 aligned for coaction with the surface of either of the cams 123 or 124. In each instance the rollers are rotatably secured to their respective arms by means, such as pins 140.

Depending lever portions 142 and 143 on the rocker arms 125 and 126, respectively, have yokes 144 and 145 at their lower ends which serve to provide connections to control operating rods 146 and 147. In each instance a connector block 148 is rotatably mounted between the arms of the yoke on studs 149 which extends through the yoke arms and into opposite sides of the connector blocks. The control operating rods 146 and 147 extend through the connector blocks 148 in a direction transverse to the axes of the studs 149.

and are slidably longitudinally relative to the connector blocks.

As indicated in Fig. 1, compression springs 150 and 152 encircle portions of each of the control operating rods 146 and 147 on opposite sides of the respective connector blocks and each have an end abutting one of the blocks. At the opposite ends of the springs, collars 153 and 154 are adjustably secured to the control operating rods and abut the outer ends of the springs to hold those springs against the ends of the connector blocks. The compression of the springs 150 and 152 in each instance is adjusted to an amount such that it will transmit sufficient force to the control operating rods from the rocker arms normally to actuate the respective control operating rods and the hoist control apparatus connected thereto. However, the springs 150 and 152 provide sufficient flexibility in the connection between the control operating rods and the respective rocker arms that in some necessary and somewhat abnormal circumstances the control operating rods can be actuated manually to positions other than those effected by the control mechanism.

In the illustrated embodiment of my invention, the cams 119 and 120 each have a contour adapted to control the deceleration of the hoist in one of its directions of movement. To effect such control, one of the rollers 136 or 137 is biased toward its respective cam by force applied to the rocker arm 142 through the control rod 146. The subsequent movements of the rocker arm 142 and control operating rod 146, which are effected by the movements and profiles of the cams 119 and 120 actuate appropriate control apparatus, such as electrical controls (not shown), which in turn determines the speed and deceleration of the hoist.

The cams 123 and 124, which are mounted in coplanar relationship, actuate the rocker arm 126 to effect control of the hoist-braking mechanism at separated hoist-stopping positions. Since the hoist-braking mechanism has only two extreme positions, i. e., "off" or "on," and intermediate variable positions for each stopping position of the hoist, it may be controlled by a single cam follower and circumferentially separated cams 123 and 124 in the same operating plane.

Referring to the diagrammatic illustration in Fig. 6, my hoist control mechanism is connected through coaxial gears 155 and 156 to be driven in definite and predetermined relationship from the hoist cable winding drum 157; the gear 155 being drivingly connected to the shaft 17 of the control mechanism and the gear 156 having positions continually related to the hoist position. Thus, the movements of the cam-carrying drum 28 are determined by the position of the hoist. Since there is no normal need for the application of the hoist brakes during the intermediate portion of the hoist travel and since that intermediate portion of the hoist travel may be at a substantially constant speed, the disclosed hoist control mechanism need not effect any variations in the hoist speed or brake setting during the time of the intermediate portion of the hoist travel. On the other hand, to promote accuracy in the hoist control at and near the ends of the hoist travel without extreme accuracy in the cam profiles and positions, the cam-carrying drum 28 desirably travels through a considerable arc of movement at and near the stopping positions of the hoist. To effect such operation of the cam-carrying drum, whereby it is driven only at the

ends of the hoist travel and at rates proportional to that of the hoist, the stops 85 and 86 on the driven gear 74 are adjusted to positions such that they engage the bearing block 65 to drive the drum when the hoist is approaching one of its limits of movement.

As the hoist moves away from one of its stopping positions, the reversal of the rotation of the shafts and gears of the hoist control mechanism from those which followed the movement of the hoist toward that position, tends to move the last engaged stop 85 or 86 away from the bearing block 65. Due to the biasing force of the weights 93, which are connected to the cam-carrying drum, the drum follows the reversed movement of the stop until it reaches its normal position determined by the position of the lug 96 thereon. Subsequent continued movement of the hoist in the same direction rotates the shafts and gears of the hoist control mechanism without turning the drum until the other one of the stops 85 or 86 engages the bearing block 65. It may thus be understood that the positions of the stops 85 and 86 are selected to effect the rotation of the cam-carrying drum when the hoist is near its limits of travel.

The positions of the hoist speed and deceleration control cams 119 and 120 are so selected that both are ineffective during the intermediate portion of the hoist travel, and each effects control of the deceleration of the hoist during its movement in one direction. The brake control cams 123 and 124 have positions on the drum such that they each effect application of the hoist brakes as they approach a stopping position in one direction. The brake control cams also retain the brake application while the hoist is stopped.

With the rocker arms 125 and 126 in the positions depicted in solid lines in Fig. 1, the hoist would be stopped at one of its stopping positions. To start the hoist from that position the brake would be manually released by force applied against the biasing force of the spring 150 and the rocker arm 125 would be moved to a position such as that illustrated in dot and dash lines at 125a, which movement of the rocker arm 125 would place the roller 136 in a position such as that indicated at 136a, wherein it is aligned for engagement with the cam 119. The initial movement of the hoist produces the resultant movement of the cam-carrying drum which moves the brake control cam away from the following roller 139 so that the biasing force of the spring 150 and brake-releasing force applied through the control operating rod 147 move the rocker arm 126 to a position such as that indicated in dot and dash lines at 126a, in which latter position the brakes remain released until the following roller 139 is engaged by the other of the brake control cams.

As indicated diagrammatically in Fig. 6, the manual force for starting the hoist in either direction is applied to the control operating rods 146 and 147 by suitable manually operable elements, such as levers 158 and 159, respectively. The lever 158, which is connected to the hoist speed control rocker arm, has three normal operating positions. The neutral position, in which the hoist is stopped, is shown in solid lines, while the positions for effecting upward and downward movements of the hoist are indicated in dot and dash lines at 158a and 158b, respectively. The brake control lever has two limiting positions; one of which is indicated in solid lines and the other of which is shown in dot and dash lines at

159a. After the hoist is started, the manual control levers follow the positions determined by the speed and brake control cams.

With the springs 150 and 152 interposed between the rocker arms and their respective control operating rods, the hoist may be moved by manual control in either direction from either of the positions at which it is stopped by the automatic control of the disclosed hoist control mechanism. Although the springs 150 and 152 are sufficiently strong to effect normal movement of the control operating rods, their respective biasing forces may be manually overcome to move the control operating rods after they have been actuated to their hoist-stopping positions by the control mechanism. In any instance, the release of the brake during the starting of the hoist is effected by actuation of the control operating rod 147 against the biasing force of one of the compression springs 150 or 152.

From the foregoing description of a preferred embodiment of my hoist control mechanism, it may be readily understood that I have provided a mechanism which renders accurate, dependable and effective control of the hoist speed and brakes, which control is continuously dependent upon the position of the hoist. The disclosed control mechanism further provides accurate control of the hoist in relation to its position without being unduly large in size and without requiring extreme accuracy in the cams and their adjusted positions. The mechanism permits manual control of the hoist position under circumstances such as the premature stopping of the hoist while it is carrying an abnormally heavy load or the like. In addition, the working parts of the mechanism are enclosed for effective lubrication and to protect them from dirt.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A hoist control mechanism adapted to be driven from the hoist drum and comprising in combination, a base providing a main support and having a main journal bearing therein, a substantially circular drum having an integral hub disposed coaxially therewith and projecting from one end thereof, said hub being journaled in said main bearing to support the drum for rotation relative to the base, and said hub having an axial opening therethrough and bearings carried therein, a shaft journaled in the last mentioned bearings and projecting from both ends of the hub, a drive gear drivingly connected to the end of said shaft opposite the drum, a pinion secured to the other end of the shaft within the drum, a driven gear, means for rotatably supporting the driven gear within the drum with its axis of rotation eccentric to that of the drum, gear and pinion means within the drum and drivingly connecting said driven gear to said pinion on the shaft, stop means within said drum and secured thereto, stop means adjustably secured to said driven gear and disposed for engagement with the stop means in the drum so that when one stop means engages the other relative rotation between the driven gear and drum is stopped and said drum is rotated by

force applied to said gear and pinion means by said pinion on the shaft, means for biasing the drum to a predetermined position relative to the base, cam means carried at peripherally adjustable positions on the exterior of the drum, cam followers carried by the base and aligned with each of said cam means, means connected to each of said cam followers for controlling the operation of the hoist, and means for rotating said drive gear in direct relationship to the rotation of the said hoist drum so that the operation of said control mechanism is directly related to the position of the hoist.

2. A hoist control mechanism adapted to be driven from the hoist drum and comprising, in combination, a base providing a main support, a substantially circular drum, means for supporting the drum relative to the base for rotation about its central axis, a shaft, means rotatably supporting the shaft coaxially with the drum, a pinion at one end of the shaft and driven thereby, means for driving said shaft from the hoist drum, a driven gear, means on said drum for rotatably supporting said driven gear, gear and pinion means supported for rotation relative to the drum and drivingly connecting said driven gear to said pinion on the shaft, stop means mounted at a predetermined position on said drum, stop means adjustably secured to said drum, stop means disposed for engagement with the stop means in the drum during rotation of the driven gear so that when one stop means engages the other relative rotation between the driven gear and drum is stopped and said drum is rotated by force applied to said gear and pinion means by said pinion on the shaft, means for biasing the drum to a predetermined position relative to the base, cam means carried at a circumferentially adjustable position on the drum,
3. A hoist control mechanism adapted to be driven from the hoist drum so as to have positions correlated to those of the hoist and comprising, in combination, support means, a drum, means for supporting the drum relative to the support means for rotation about a central axis, a shaft, means rotatably supporting the shaft in coaxial relationship to the drum, means for drivingly connecting the shaft to the hoist drum, a pinion on said shaft and driven thereby, a rotary driven element, means on said drum for rotatably supporting said driven element, intermediate drive means carried by said drum for drivingly connecting said pinion to the rotatable driven element, stop means secured to said drum at a predetermined position, additional stop means secured to said driven element and disposed for engagement with the first mentioned stop means during rotation of the driven element so that when one stop means engages the other relative rotation between the driven element and drum is arrested and said drum is rotated by force applied through said pinion, means for biasing said drum to a predetermined position relative to the support means,
4. A hoist control mechanism as defined in

claim 3 wherein said means for biasing the drum to a predetermined position relative to the support means comprises pulley means rotatably carried by the support means, flexible means extending over said pulley means and having one end connected to said drum at a predetermined position, and a weight suspended at the other end of said flexible means.

5. A hoist control mechanism adapted to be driven from the hoist drum so as to have positions correlated to those of the hoist and comprising, in combination, a cam-carrying drum, means for rotatably supporting said cam-carrying drum for movements between predetermined limiting positions, a pair of similarly shaped cams secured to the cam-carrying drum in oppositely disposed and symmetrical relationship to one another, means for biasing the cam-carrying drum to a predetermined position, a cam follower for each of said cams, driving means including a series of gears for drivingly connecting said gears to said hoist drum for operation at a rate proportional to movements of the hoist drum and in a direction dependent upon that of the hoist drum, separated means on one of the gears of said driving means effective during opposite directions of movement of said one of the gears for drivingly connecting said one of the gears and said cam-carrying drum to effect movement of the cam-carrying drum away from said predetermined position, the separation of said separated means being such that said one of the gears has a period of rotation relative to the cam-carrying drum during movement of the drum between said limiting positions in each direction, and hoist control means responsive to movements of each of the cams.

6. A hoist control mechanism adapted to be driven from the hoist drum so as to have positions correlated to those of the hoist and comprising, in combination, a cam-carrying drum, means supporting said cam-carrying drum for rotary movement through less than half of one revolution in each direction from a predetermined position, means for biasing the cam-carrying drum to said predetermined position, a pair of hoist speed control cams secured to the cam-carrying drum in axially displaced positions thereon, a pair of hoist brake control cams secured to the cam-carrying drum in circumferentially displaced relationship to one another, a first cam follower means having rollers spaced circumferentially of the cam-carrying drum, each of said rollers being aligned axially of the drum with one of the hoist speed control cams, a second cam follower means having a roller aligned axially of the drum with said brake control cams, means biasing one or the other of the rollers of said first cam follower means toward the path of the cam with which it is aligned, the one of said rollers thus biased toward the cam path being dependent upon the direction of operation of the hoist, means for biasing said roller of the second cam follower means toward the path of the brake control cams during movement of the hoist in either direction, hoist control means responsive to each of said cam follower means, means driven by the hoist drum, and means effective at a predetermined position of the last mentioned means during movement of the hoist in each direction for rotating said cam-carrying drum.

7. A hoist control mechanism adapted to be driven from the hoist drum so as to have positions correlated to those of the hoist and comprising, in combination, a cam-carrying drum, 75

means supporting said cam-carrying drum for rotary movement through less than half of one revolution in each direction from a predetermined position, means for biasing the cam-carrying drum to said predetermined position, hoist control cam means secured to the cam-carrying drum, cam follower means aligned for coaction with said cam means, means for biasing the cam follower means toward the path of the cam means when the hoist is in operation, hoist control means responsive to movements of said cam follower means, means driven by the hoist drum, and means effective at predetermined positions of the last mentioned means during movements of the hoist for rotating said cam-carrying drum.

8. In a hoist control mechanism adapted to be driven from the hoist drum so as to have positions correlated to those of the hoist, drive means 20 for a rotary control drum comprising a shaft, means rotatably supporting the shaft in coaxial relationship to the drum, means for drivingly connecting the shaft to the hoist drum, a pinion on said shaft and driven thereby, a rotary driven 25 element, means on said drum for rotatably supporting said driven element, intermediate drive means carried by said drum for drivingly connecting said pinion to the rotatable driven element, stop means mounted at a predetermined 30 position on said drum, additional stop means secured to said driven element and disposed for engagement with the first mentioned stop means during rotation of the driven element so that when one stop means engages the other relative 35 rotation between the driven element and drum is arrested and said drum is rotated by force applied through said pinion, and means for biasing the control drum to a predetermined position.

9. In a hoist control mechanism adapted to be 40 driven from the hoist-lifting mechanism so as to have positions correlated to those of the hoist, the combination of drive means for a rotary control drum comprising a rotary driven element, means on said drum for rotatably supporting said 45 driven element, means for drivingly connecting the driven element to the hoist-lifting mechanism, a first stop mounted at a predetermined position on said drum, and a second stop secured to said driven element and disposed for engagement with the first stop during rotation of the driven element so that when one stop engages the other relative rotation between the driven element and the drum is arrested and said drum is rotated by force applied through the stops.

10. The combination defined in claim 9 wherein 55 in said second stop is circumferentially adjustable relative to the driven element and engages the first stop during rotation of the driven element in one direction, and a third stop is adjustably secured to the driven element for engaging the first stop during rotation of the driven element in the opposite direction.

11. In a hoist control mechanism adapted to 60 be driven from the hoist-lifting mechanism so as to have positions correlated to those of the hoist, the combination of a cam-carrying drum, means supporting said cam-carrying drum for rotary movement through less than half of one revolution in each direction from a predetermined position, means for biasing the cam-carrying drum to said predetermined position, a pair of hoist speed control cams secured to the cam-carrying 65 drum in axially displaced positions thereon, a pair of hoist brake control cams secured to the cam-carrying drum in circumferentially dis-

placed relationship to one another, a first cam follower means having rollers spaced circumferentially of the cam-carrying drum, each of said rollers being aligned axially of the drum with one of the hoist speed control cams, a second cam follower means having a roller aligned axially of the drum with said brake control cams, means biasing one or the other of the rollers of said first cam follower means toward the path of the cam with which it is aligned, the one of said rollers thus biased toward the cam path being dependent upon the direction of operation of the hoist, means for biasing said roller of the second cam follower means toward the path of the brake control cams during movement of the hoist in either direction, hoist control means responsive to each of said cam follower means, and resilient means interposed between each said hoist control

means and the cam follower to which it is responsive so that each hoist control means can be actuated against the force of said resilient means and independently of the said hoist control mechanism.
